UNITED STATES PATENT OFFICE.

FRANK A. WILCOX, OF ERIE, PENNSYLVANIA.

DESIGN FOR A BICYCLE-PEDAL RUBBER.

SPECIFICATION forming part of Design No. 33,143, dated August 28, 1900.

Application filed June 20, 1900. Serial No. 21,020. Term of patent 3½ years.

To all whom it may concern:

Be it known that I, FRANK A. WILCOX, a citizen of the United States, residing at Erie, in the county of Erie and State of Pennsylvania, have invented and produced a certain new and original Design for Bicycle-Pedal Rubbers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 The leading features of my design consist in the shape and configuration of a bicycle-pedal rubber embodying substantially a rectangular block of rubber having a longitudinal slot therein and having a central extension projecting downward for a short distance from one side of the slot therein and turning outward at right angles therefrom.

20 Figure 1 is a perspective view of a bicycle-pedal rubber embodying my design. Fig. 2

25 is a perspective view of the under surface thereof.

In the drawings, A is the body of the pedal-rubber, the top of which is rectangular in shape and finished with checker-work a. The corners a' of the under surface of the 30 body A are cut away, and there is a central longitudinal slot B, which extends upward into the body A for the entire length thereof. Centrally from one side of the slot B there is an extension d, projecting downward and parallel with the side of the slot B for a short distance and then extending outward at right angles, so as to form a lateral projection d' thereon, and through this lateral projection d' there is a hole d².

Having thus described my design, what I claim is—

The design for a bicycle-pedal rubber, substantially as shown and described.

In testimony whereof I affix my signature 45 in presence of two witnesses.

FRANK A. WILCOX.
